PRECISION POTENTIOMETER
Randolph E. Charles, Wayland, Mass. (4 Gordon St.
(Room 112), Waltham 54, Mass.)
Filed Feb. 3, 1961, Ser. No. 87,038
4 Claims. (Cl. 338—157)

This invention relates to electrical current regulating devices and more particularly to devices for varying the resistance in an electric circuit. Such devices are commonly called potentiometers.

The usual potentiometer consists in essence of a first element of relatively high resistance which is contacted slidably by a second element. The two elements are connected in series in the circuit, the first element being disposed in such manner that as the second element slides along the first element the electrical current must pass through an increasingly larger segment of the first element, thereby increasing the resistance in the circuit. The configuration of the first element is usually a high resistance wire wound on a core of insulating material which generally is flat or circular.

Regardless of the configuration of the resistance element, the prior art potentiometers have always included someplace in the circuit engaging elements which slide with respect to each other. By its very nature, a sliding contact creates electrical "noise," and this "noise" produces an adverse effect on the operation of the circuit.

Another disadvantage in sliding contact devices is found in the wear which the sliding contact causes on the resistance element. Where a resistance wire is wound spirally around a base or core, the pressure of the sliding contact thereon coupled with the friction of its sliding causes a high rate of wear.

Accordingly, it is an object of my invention to provide a potentiometer in which there is no loss of accuracy or usefulness due to contact "noise" or sliding friction.

It is another object of my invention to provide a potentiometer in which the resistance element will be subjected to a minimum of forces which tend to cause it to wear out, as, for example, by sliding the contact over it.

It is a further object of my invention to provide a potentiometer in which the path of the electrical current at no point passes through a sliding connection.

In the practice of my invention in a preferred embodiment thereof, I construct a potentiometer having two rings of equal interior radius mounted coaxially. One ring serves as a commutator and the other is wound with resistance wire and serves as the resistance element. A one-piece roller, with its ends engaging the interior surfaces of the commutator and resistance wire, is disposed on a spring loaded arm extending transversely of the two rings and serves as the contact member. The roller carrying arm is positioned on a shaft whereby it may be caused to move the roller around the inside face of the two rings. As the roller is rolled away from the beginning of the resistance element, the resistance in the circuit is increased.

It is a feature of my invention that the current flow through the commutator, roller and resistance element is accomplished without its passing through any sliding contact.

It is another feature of my invention that the roller engages the resistance element ring in a substantially frictionless contact.

It is a further feature of my invention that substantially greater pressure than has heretofore been feasible may be employed to engage the roller with the resistance ring while at the same time the useful life of the resistance wire is substantially increased.

These and other objects and features of my invention

2

will appear as the description proceeds with the aid of the accompanying drawings, in which:

FIG. 1 is a sectional view of a potentiometer according to my invention taken along the line 1—1 of FIG. 2;

5 FIG. 2 is a section along the line 2—2 of FIG. 1;

FIG. 3 is a fragmentary section along the line 3—3 of FIG. 2; and

FIG. 4 is a diagrammatic exposition of my invention.

10 Referring to FIG. 4 for an explanation of the theory of my invention, a commutator bar 10 is shown having a lead wire 12 whereby it may be connected into an appropriate electric circuit (not shown). In spaced parallel relation to the commutator 10 is positioned a resistance element indicated at 14. The resistance element 14 comprises an insulated bar 16 around which a resistance wire 18 is wound. A contact member indicated at 20 is positioned to engage the commutator 10 and resistance element 14 and comprises a center shaft 22 of any suitable diameter and roller wheels 24 likewise of any suitable diameter which are formed integrally with the shaft 22. It is obvious that the contact member 20 may be rolled substantially without friction along the commutator 10 and resistance element 14, thereby varying the resistance in the circuit.

25 Referring now to FIGS. 1, 2 and 3 for a more particular description of a preferred embodiment of my invention, I provide a housing indicated at 26 which may be constructed of any suitable material and need not be electrically non-conductive. In practice, the housing 26 has a cylindrical wall 28 and a flat circular end wall 30.

30 Within the housing, I position a first insulating sleeve 32 which engages the housing 26 snugly and fits against the end wall 30. The purpose of the insulating sleeve 32 is to electrically insulate the housing 26 from a resistance element indicated at 34. The resistance element 34 comprises a sleeve of insulating material 36 around which a resistance wire 38 is wound, each turn spaced from the next. The sleeve 34 extends around the insulating sleeve 32 for nearly the entire circumference. An end 40 of the wire 38 passes through a short insulating member 42 to the outside of the housing 26 where it terminates in a binding post 44.

35 A second insulating sleeve 46 is positioned snugly within the housing 26 parallel to and spaced apart from the insulating sleeve 32, and a circular commutator 48 is positioned within it. The commutator 48 is connected to a wire 50 which passes through an insulating member 52 to the outside of the housing 26 where it terminates in a binding post 54.

40 In order to provide means for engaging the commutator 48 and resistance element 34, a central shaft 56 is first positioned extending along the common axis thereof. This is accomplished by providing a short cylindrical bearing 58 extending inwardly from the end wall 30 and dimensioned to engage one end of the shaft 56. The other end of the shaft 56 passes through a bearing 60 formed in a cover 62 which completes the housing 26. The shaft 56 is thus rotatably positioned in the bearings 55 58 and 60. A handle 62 is provided for rotating the shaft 56.

45 Positioned on shaft 56 is an arm 64 which at one end is divided as at 66 whereby it may be clamped on shaft 56 by a bolt 68. An electrically non-conductive bushing 67 is positioned between the arm 64 and shaft 56 to prevent any electrical current in the arm 64 from passing to the shaft 56. The arm 64 is formed at one end into a fork indicated at 70 (see FIG. 3) and having spaced side elements 69 and 71.

50 A rocker arm 72 is pivotally disposed in the fork 70 on a pivot member 74 which is mounted through the elements 69 and 71. An end 76 of the rocker arm 72 ex-

tends beyond the fork 70 and is attached to a coiled tension spring 78. The spring 78 is also attached to the arm 64 and tends to pull the end 76 toward the arm 64. The opposite end 80 of the rocker arm 72 likewise extends beyond the fork 70 and is formed to receive the outer race 82 of a ball bearing in which the inner race is indicated at 86 and the ball at 84. Inner race 86 is firmly engaged on the shaft segment 88 of a contact member indicated at 90.

The contact 90 comprises a roller or "dumbbell" shaped member having shaft 88 and rolling segments 92 and 93. The contact 90 is dimensioned so that one end 92 will travel over the commutator 48 and the other end 93 over the wires 38 of resistance element 34. Contact 90 is of unitary construction and is made of any suitable material of good electrical conductivity.

The operation of my invention is as follows: The potentiometer is connected into the desired electrical circuit through binding posts 44 and 54. The current in the circuit then flows through commutator 48, contact 90, and resistance element 34. By rotation of handle 62, the position of contact 90 on resistance element 34 may be changed, thereby changing the over-all resistance of the unit. It will be noted that at no point does the current flow through a sliding connection. End elements 92 and 93 of contact 90 are of the same diameter, are integral with shaft 88 thereof and rotate with relation to commutator 48 and resistance element 34, which also are of the same internal diameter. Since the contact is rolling, not sliding, the resistance wire 38 may be of very fine fabrication and the pressure of end segments 92 and 93 against resistance element 94 may safely be substantially greater than would be possible with a sliding contact.

It should be noted that my construction reduces contact "noise" to an extremely low level by eliminating any sliding contact.

It is my intention to claim all changes and modifications of the preferred embodiment of my invention herein chosen for purposes of disclosure which do not constitute departures from the spirit and scope of the invention.

I claim:

1. A potentiometer comprising a base, a first insulating sleeve mounted on said base, a commutator comprising a sleeve of electrically conductive material having a low resistance mounted within said first insulating sleeve, a second insulating sleeve mounted on said base parallel to said first insulating sleeve, a resistance element comprising an insulating core having a wire of high resistance wound therearound positioned within said second insulating sleeve and being of equal interior radius and coaxial with said commutator, rolling means for making an electrical contact between said commutator and said resistance element, means for moving said rolling means

around said commutator and said resistance element in a circular path coaxial with said commutator and resistance element and inside thereof, and means for urging said rolling means firmly against said commutator and resistance element.

2. A potentiometer as defined in claim 1, further characterized by said rolling means comprising a shaft positioned by said moving means parallel to the common axis of said commutator and said resistance element, end segments on said shaft and integral therewith and having a substantially cylindrical configuration and engaged on said commutator and said resistance element with the axis of said cylindrical end segments common with the axis of the said shaft.

3. A potentiometer as defined in claim 1, further characterized by said means for moving said rolling means comprising a shaft rotatably disposed on said base along the axis of said commutator and said resistance element, a first arm releasably engaged on said shaft, means for insulating said arm electrically from said shaft, said means for urging said rolling means against said commutator and resistance element comprising a fork formed at the outer end of said arm, a second arm pivotally disposed in said fork element, a first end on said second arm extending beyond said fork element, a coiled spring connected to said first end of said second arm and to said first arm to draw said first end downwardly toward said shaft, a second end on said second arm extending beyond said fork element and opposite to said first end thereof, a ball bearing positioned in said second end of said second arm having an outer race engaged therewith and an inner race for receiving the said contact making rolling means.

4. A potentiometer comprising a circular insulating core having a resistance wire wound thereon, a circular commutator having the same inside diameter as said resistance wire covered core, said core and commutator being parallel and coaxial, said core and commutator having means at their one ends for connecting them into a circuit, a roller contacting element having end portions of the same diameter, one end portion engaging the resistance wire and the other end portion engaging the commutator, means for causing said contacting element to roll about the interiors of said resistance wire and commutator, whereby the resistance in said circuit may be varied, and means for holding said contacting element against said resistance wire and commutator with a substantially constant pressure.
